Primary Examiner — George D. Kirschbaum*Assistant Examiner* — Lacey Chey Bowman(74) *Attorney, Agent, or Firm* — Hayes Soloway P.C.(57) **CLAIM**

The ornamental design for a video recorder for vehicle as shown and described.

DESCRIPTION

FIG. 1.1 is a perspective view of the top and front of a video recorder for vehicle showing my new design;

FIG. 1.2 is a front elevational view thereof;

FIG. 1.3 is a back elevational view thereof;

FIG. 1.4 is a left-side elevational view thereof;

FIG. 1.5 is a right-side elevational view thereof;

FIG. 1.6 is a top plan view thereof;

FIG. 1.7 is a bottom plan view thereof;

FIG. 1.8 is an enlarged portion view taken from encircled portion labeled, “1.8,” in FIG. 1.4; and,

FIG. 1.9 is an enlarged portion view taken from encircled portion labeled, “1.9,” in FIG. 1.5.

The dashed-dot lines form the boundary of the enlarged portion views of FIGS. 1.8 and 1.9 in FIGS. 1.4, 1.5, 1.8, and 1.9 and form no part of the claimed design. The even dashed broken lines shown in the drawings are included for the
